UNITED STATES PATENT OFFICE

SIDNEY C. PROBERT AND ROBERT E. SPURR, OF DETROIT, MICHIGAN, ASSIGNORS, BY MESNE ASSIGNMENTS, TO CHRYSLER CORPORATION, A CORPORATION OF DELAWARE

TRUING ATTACHMENT FOR GRINDING MACHINES

Original application filed October 10, 1924, Serial No. 742,770. Divided and this application filed October 5, 1927. Serial No. 224,121.

This invention relates to grinding machines, and more particularly to truing attachments for grinding discs thereon. This application is a division of our earlier application, Serial No. 742,770, filed October 10, 1924.

The invention is particularly designed to be applied to machines for grinding twist drills. Certain features thereof, however, are not limited to drill grinding machines but may be applied with advantage to other grinding machines.

It is highly important in grinding twist drills that the drill should be accurately ground according to certain specifications in order that the drill may cut with the proper speed and accuracy. In order to grind a drill accurately, the grinding surfaces of the grinding members should be kept accurately true. To secure this result, the grinding discs of drill grinding machines are usually provided with a truing mechanism for truing up the grinding surfaces of the grinding discs. Such a truing mechanism usually comprises a truing tool which is adjustable toward and from the grinding surface of the grinding disc to bring the tool into and out of contact with the disc and is also adjustable across such surface in a direction substantially parallel therewith so that the tool may traverse the grinding surface of the disc.

The principal object of the present invention is to improve the construction and mode of operation of truing mechanisms for truing up the surfaces of grinding discs and to provide an improved mechanism by which the adjustments required to bring the truing tool into contact with the grinding surface of the disc and to cause the tool to traverse said grinding surface, may be quickly and accurately effected.

With this object in view, the invention consists in a truing mechanism involving the novel and improved features, constructions and combinations of parts hereinafter described and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings:

Figure 1 is a view in front elevation of a portion of a drill grinding machine provided with truing devices embodying the invention;

Figure 2 is a view in side elevation illustrating the mechanism for truing up one of the grinding discs looking from the left of Figure 1; and

Figure 3 is a view in side elevation illustrating the devices for truing up the other grinding disc looking from the right of Figure 1.

The machine embodying the present invention as illustrated in the drawings, comprises two rotary grinding discs 2 and 4 secured to the opposite ends of a shaft 6 mounted in bearings 8 formed on a bracket 10 secured to the upper end of a standard or bench of usual form. Upon the shaft 6 is mounted a belt pulley 14 about which passes a suitable driving belt (not shown). Each of the grinding discs is provided with a central recess extending inwardly from the outer face of the disc, as indicated in dotted lines.

The tool for truing up the grinding disc 2 is indicated at 170. This tool is supported in position to engage the outer lateral face of the grinding disc adjacent its periphery with which the drills are engaged in grinding the same. The tool 170 is secured in a laterally extending arm on a slide 172 arranged to slide in a direction transverse to the plane of the grinding disc and preferably perpendicular to said plane. The slide 172 is supported on a slide 174 mounted to slide on the frame of the machine, preferably in a direction substantially parallel with the plane of the grinding disc. The movement of the slide 172 carries the truing tool into and out of position to engage the lateral face of the grinding disc, while the movement of the slide 174 carries the acting end of the tool across the surface to be trued in a direction substantially radial to the disc.

The slide 172 is adjusted by mechanism 100

comprising a shaft 176 rotatably mounted in the slide and held from longitudinal movement therein, the inner end of which shaft is threaded into the slide 174. The shaft 176 has a hand wheel 177 secured to the outer end thereof to enable the shaft to be rotated manually.

The slide 174 is adjusted by mechanism comprising a shaft 180 rotatably mounted in the slide and held from longitudinal movement therein, the inner end of which shaft is threaded into the frame of the machine. The shaft 180 carries a hand wheel 181 secured to its upper end.

The truing tool for truing up the grinding disc 4 is indicated at 182 (Figure 3). This truing tool is supported in position to engage the periphery of the grinding disc 4. The tool is secured in an arm on a slide 184 arranged to slide in a direction transverse to the plane of the grinding disc and preferably perpendicular to said plane. The slide 184 is mounted on a second slide 186 arranged to slide in a direction preferably parallel with the plane of the grinding disc. The movement of the slide 186 carries the grinding tool into and out of engagement with the periphery of the grinding disc and the movement of the slide 184 carries the acting end of the tool across the peripheral surface of said disc. The slide 184 is adjusted by a mechanism comprising a shaft 188 rotatably mounted in said slide and held from longitudinal movement therein, the inner end of which shaft is threaded into the slide 186. A hand wheel 190 is secured to the outer end of the shaft 188 to enable the same to be manually rotated. The slide 186 is adjusted by a mechanism comprising a shaft 192 rotatably mounted in the slide 186 and held from longitudinal movement therein, the inner end of which shaft is threaded into the frame of the machine. A hand wheel 194 is secured to the upper end of the shaft 192.

To enable the lateral face of the grinding disc 4 to be trued up if desired, the slide 184 is provided with an arm in which may be secured a second truing tool 196 arranged to engage the lateral face of the grinding disc. This tool may be adjusted in a direction transverse to the plane of the grinding disc and in a direction radial to the disc by adjustment of the hand wheels 190 and 194 respectively.

It is to be understood that the invention is not limited to the particular construction and arrangement of parts of the illustrated embodiment of the invention but that the invention may be embodied in other forms within the scope of the claims.

What is claimed as new is:

1. A grinding machine having in combination a grinding wheel to be trued; truing tools, one for the face of the wheel and another for the periphery thereof, and mech-

anism for so moving said tools that the truing movement of each tool serves to adjust the other tool towards or away from its contact with the wheel.

2. A grinding machine having in combination a grinding wheel to be trued, a truing tool, a mounting therefor arranged to carry the tool radially into contact with the lateral face of the wheel, a second truing tool, a mounting therefor arranged to carry the second tool into contact with the periphery of the wheel, said mountings being so interconnected that the movement of one tool across the lateral face of the wheel moves the other tool towards or away from contact with the periphery of the wheel.

3. A grinding machine having in combination a rotary grinding disc, a slide mounted for movement in a direction substantially parallel with one face of the grinding disc, a second slide mounted on the first slide for movement in a direction substantially parallel with another face of the grinding disc, a truing tool for one face and a second truing tool for the other face both mounted on the latter slide in such relation that one tool is carried into or away from operative contact with its face of the wheel by the same movement which carries the other tool across its face of the wheel in a truing operation.

4. A grinding machine having in combination a grinding wheel, a truing tool for one face of the wheel, another truing tool for another face of the wheel, and a single carriage for said tools capable of moving in directions respectively parallel to the faces of the wheel which are to be trued, said tools being connected to the carriage in such relation that one tool is brought into operative contact with its face of the wheel at the end of the movement by which the other tool is caused to true its face of the wheel.

Signed at Detroit, Michigan, this 29th day of September, 1927.
